DISPENSER

George P. Haag, Chicago, Ill.

Application November 15, 1940, Serial No. 365,831

2 Claims. (Cl. 284—19)

This invention relates to dispensers and, more particularly, to an improved dispenser for use in conjunction with beer barrels and other liquid containers.

One object of the invention is to provide a dispenser which may be quickly attached to a beer barrel or the like and which will, when attached, insure ready insertion of a draft pipe in the barrel for permitting drawing of the contents thereof and without interfering with supply pipes or the like.

Another object of the invention is to provide a dispenser which may be readily attached to beer or other fluid containing barrels without the need of wrenches or other tools, the use of which would interfere with the tapping of the barrel.

A further object of the invention is to provide a dispenser employing a one piece body having a valve therein which will be operative for sealing the barrel or keg upon withdrawal of the draft tube without loss of pressure from the keg or barrel.

Another object of the invention is to provide a dispenser having a one piece body which forms a housing for both the sealing valve and the gas inlet valve employed.

A further object of the invention is to provide a device of this character employing an improved automatic inlet valve for gas or other fluid under pressure.

A still further object of the invention is to provide a dispenser wherein the fluid pressure valve employed eliminates the need for closing valves on the gas pressure line when the gas pressure is relieved from the barrel.

And a still further object of the invention is to provide a dispenser of this character which is simple in construction and which will be highly efficient in use.

Other objects of the invention, not specifically mentioned hereinbefore, will become apparent during the course of the following description.

In the drawing forming a part of my application,

Figure 1 is a vertical sectional view showing my improved dispenser as it would appear in operative position on a barrel or keg, with a draft tube in position extending therethrough and into the barrel.

Figure 2 is a vertical detail sectional view on the line 5—5 of Figure 1.

Figure 3 is a vertical detail sectional view on the line 6—6 of Figure 1.

Figure 4 is a detail side elevation, partly in

section, showing the detachable elements of the gas pressure valve, and

Figure 5 is a detail sectional view, partly in elevation, of the gas pressure valve.

Referring now more particularly to the drawing, wherein like numerals of reference designate like parts throughout the several views, the numeral 1 indicates in general the body of my improved dispenser. The body is formed with an exteriorly threaded depending tubular shank 2 on which is screwed a connecting sleeve 3, said connecting sleeve having a bayonet connection 4 for engagement with a mating bayonet connection 5 on the top wall 6 of a barrel or keg. Carried within the connecting sleeve 3 is a compression ring 8, and disposed beneath the compression ring is a packing ring 9. As best seen in Figure 1, when the device is installed on a barrel, the connecting sleeve is screwed down upon the shank a sufficient distance past the end of said shank so that the mating bayonet elements 4 and 5 may be properly engaged. The sleeve 3 is, however, moved such a distance that, when the connecting sleeve is rotated to lock the bayonet connection, the compression ring 8 will compress the sealing gasket or packing ring 9 and thus insure a tight seal between the body 1 and the head 6 of the barrel or keg.

The body 1 is formed with an integral upwardly enlarged valve chamber 10, said valve chamber having a flange 11 at its upper rim and being formed with an integral gas inlet pipe 12, said gas inlet pipe having an enlarged free end portion defining a combined coupling and gas pressure valve element 13, said gas pressure valve construction to be described in more detail hereinafter.

Normally closing the top of the valve chamber 10 is a cover 14, said cover having a wall 15 and an integral gland 16. The wall 15 is secured to the flange 11 of the valve chamber 10 by means of screws 17, a suitable gasket 18 being disposed between the wall 15 and the upper surface of the rim 11 to prevent leakage. The wall 15 is provided with an axial opening 19 which communicates between the interior of the gland 16 and the interior of the valve chamber 10, said opening being in vertical alignment with the tubular shank 2, which shank is in communication with the interior of the valve chamber 10 and the interior of the barrel or keg 7. Mounted within the gland 16 and extending about the opening 19 thereabove is a packing washer 20. As will be seen in Figure 1, the gland 16 is interiorly threaded and receives the threaded shank 21 of

a sealing nut 22, the nut having a relatively large manually engageable portion 23. Attention is particularly called to the fact that the lower edge of the opening 19 defines a valve seat, which, for convenience, has been indicated at 24.

The wall 15 has mounted on its lower surface a yoke 25. The yoke 25 hingedly mounts a valve member 26, said valve member having an attaching shank 27, which extends between the arms of the yoke 25 and is swingingly connected therewith by means of a pin 28. The valve member 26 includes a circular supporting face 29 on which is mounted a valve element 30 which is formed of rubber, fiber, or other suitable material. The valve element 30 is secured to the face 29 by a screw having a round head 31, the purpose of which will be set forth presently. The valve member 26 is normally urged toward the valve seat 24 by means of a spring 32 which has a bow 33 engageable with the rear of the supporting face 29 and free end portions which are engaged with the wall of the valve chamber 10, the spring having central portions coiled about the pin 28, as shown at 34.

The construction of the gas or fluid pressure valve will now be set forth in more detail. The gas pressure valve includes the coupling element 13 and a detachable valve element 35, said valve element including an inlet nozzle 36 which is reduced and ribbed to receive conveniently the end of a rubber fluid supply tube 37.

The valve element 35 is formed with a recess 38 which communicates with the opening 39 of the nozzle 36. The element 35 is formed with an integral cage 40 which is formed on the end face 41 of said element, said end face 41 being flat and carrying a gasket 42. As will be seen, the gasket 42 lies against the flat face 41 of the element 35 in surrounding relation to the cage 40. The cage 40 defines a valve chamber 43 which communicates with the recess 38. The cage 40, further, is formed with a threaded mouth 44 into which is screwed a guide sleeve 45, said guide sleeve having an inner rim defining a valve seat 46.

Mounted within the valve chamber 43 is a spring pressed valve 47, which, as best seen in Figure 5, is normally engageable with the valve seat 46. The valve 47 is formed with an axially disposed stem 48 which extends into the recess 38 and provides a guide for one end of an expansion spring 49, the other end of said spring being engageable against the inner wall of the recess, said spring urging the valve 47 toward the valve seat 46.

The coupling 13 is interiorly threaded at its base, as shown at 50, and screwed into the threaded base is a valve opening element 51, said valve opening element having an actuating sleeve 52 and a nipple 53, said nipple extending into the pipe 12 which, as best seen in Figure 1, is formed with a slightly enlarged bore 54. Carried on the nipple 53 within the bore 54 is a rubber check valve 55. As clearly seen in Figures 3 and 4 of the drawing, the coupling 13 and the valve element 35 are formed with mating bayonet elements 56 and 57, the elements 56 being mounted on the inner rim of the coupling 13 and the elements 57 being mounted on the free end of the cage 40. As will be seen, the elements 57 are formed with inclined walls 58 which ride on the inner walls of the elements 56. It will also be noted that the elements 56 are diametrically disposed on the coupling 13 and the elements 51 are likewise disposed on the valve element 35.

In order to permit easy manipulation of the valve element 35, I provide a handle 59 which is formed integrally on said valve element.

The operation of my improved dispenser will now be described. As previously stated, my improved dispenser is attached to the wall 6 of a barrel by engagement of the mating bayonet elements 4 and 5, the connecting sleeve 3 being screwed on the shank to such a position that the ring 8 will compress the sealing ring 9 when the bayonet elements are turned home. The valve member 25a of the dispenser will, when the dispenser is in inoperative position, be in engagement with the valve seat 24 for sealing the keg or barrel and preventing escape of air or gas therefrom. In this connection, it is desired to state that the check valve 55 will also operate to prevent escape of gas from the dispenser and keg.

When it is desired to draw from the contents 20 of the barrel, it is only necessary to insert a draft tube, shown at 60, through the sealing nut 22 and the body 1 into the barrel. The draft tube when being moved to operative position, will function to drive the bung in the bunghole 61 into the barrel. After the draft tube has been moved to the keg or barrel the nut 22 is turned for engaging the sealing gasket 20 tightly about said draft tube for preventing leakage. It is desired particularly to call attention to the fact that, as the draft tube moves downwardly, the end thereof engages the round head screw 31 of the valve member 25a and swings said valve member downwardly and laterally within the chamber 10 to the position shown in Figure 1. 25 The provision of the round head screw 31 prevents any damage to the valve element 30 by the end of the draft tube when said valve is being unseated.

It is assumed for purposes of illustration that 40 there is a sufficient amount of pressure within the barrel or keg to force the beer or other liquid upwardly through the draft tube. If this condition prevails, the valve element will be out of engagement with the coupling 13. As stated, the 45 check valve 55, together with the gaskets 9 and 20, will effectively prevent escape of pressure from the barrel or keg. Let it now be assumed that the pressure within the keg or barrel 7 is not sufficient to force the liquid through the draft tube. 50 In order to supply additional pressure, it is only necessary to attach the valve element 35 to the coupling 13. This is done by manipulating the handle 59 for interengaging the bayonet connecting elements 56 and 57. As the bayonet 55 connecting elements are being turned home, the actuating sleeve 52 will pass through the guide sleeve 45 and into engagement with the valve 47, thus unseating the valve and permitting flow of gas or other fluid from the tube 37, which is, 60 of course, connected to a supply of fluid under pressure, through the bore 39, the recess 38, the chamber 43, the element 51 and the check valve 55 into the pipe 12 and, thence, into the chamber 10 downwardly about the tube 60 into the barrel. When a sufficient amount of gas under pressure has been placed in the barrel, it is only necessary to grasp the handle 59 and partially rotate the valve element 35 for permitting unlocking of the bayonet elements 56 and 57. When this 70 is done, the valve element 35 is removed from the coupling 13, which action will cause displacement of the actuating sleeve 52 from the guide sleeve 45. The compression spring 49 will then urge 75 the valve 47 into engagement with the valve seat

46 for stopping the flow of gas under pressure from the pipe 37.

During the operation of placing of gas under pressure in the barrel or beg, the gasket 42 will effectively prevent escape of fluid from between the coupling 13 and the valve element 35.

When it is desired to remove the tube 60, the nut 22 is loosened for loosening the packing 20. The tube is then withdrawn from the body. As the lower end of the pipe passes upwardly through the valve chamber 10, the valve member 25^a will be urged by the spring upwardly into engagement with the valve seat 24. It is to be noted that the packing gasket 20 is disposed above the valve seat so that said valve member will be permitted to become fully seated before the lower end of the tube 60 has cleared the said gasket 20. It will thus be seen that there will be no loss of pressure incident to the removal of the draft tube from the dispenser.

Having thus described the invention, what is claimed as new is:

1. A valve controlled pipe coupling comprising a relatively stationary coupling member having one end thereof enlarged to form a chamber open at its outer end and a reduced neck at its inner end, a valve opening element including an actuating sleeve projecting within the chamber, a check valve disposed within the neck and engaging the adjacent end of the actuating sleeve, a movable coupling member detachably engaging the stationary coupling member and provided with a tubular cage, a guide sleeve fitting within the cage around the actuating sleeve and provided with a valve seat, a main valve carried by the movable coupling member and engaging said seat, a gasket interposed between the stationary and movable coupling members, and a finger piece carried by the movable coupling 40

member for rotating the same to compress the gasket and force the actuating sleeve against the main valve to unseat said main valve when said members are coupled, and means for holding the coupling members in assembled position.

2. A valve controlled pipe coupling comprising a relatively stationary coupling member having one end thereof enlarged to form a chamber open at its outer end and a reduced tubular neck at its inner end, the interior walls of which are threaded, coupling lugs projecting inwardly from the walls of said chamber, a valve opening element engaging said threads and having one end thereof provided with an actuating sleeve extending within the chamber and its other end formed with a nipple projecting within the neck, a check valve fitting around the nipple, a movable coupling member detachably engaging the stationary coupling member and provided with a tubular cage, the interior walls of the cage being threaded and the exterior walls thereof provided with coupling lugs coaxing with the first mentioned coupling lugs, a guide sleeve engaging the threads on the cage and fitting around the actuating sleeve, said guide sleeve being provided with a terminal valve seat, there being a recess formed in the movable coupling member and disposed in longitudinal alinement with the actuating sleeve, a main valve disposed within the cage, a spring housed within said recess and engaging the main valve for holding the valve to said seat, a gasket interposed between the stationary and movable coupling members, and an operating handle projecting laterally from the movable coupling member for rotating the same to compress the gasket and force the actuating sleeve against the main valve to unseat said valve when said members are coupled.

GEORGE P. HAAG.
